UNITED STATES PATENT OFFICE.

FREDERICK J. HOYT, OF NEW YORK, N. Y.

IMPROVEMENT IN INDICATOR-PADLOCKS.

Specification forming part of Letters Patent No. 124,270, dated March 5, 1872.

Specification describing a new and useful Improvement in Register-Lock, invented by FREDERICK J. HOYT, of the city of New York, in the county and State of New York.

My invention consists of a combination, with a lock, of a rolled and numbered paper strip and apparatus for causing said strip to be forced out of the case the distance of one number by the key each time it is turned, in order that the person locking the lock may tear off the number thrust out, to be kept for comparison with the numbers torn off by others to show whether the lock has been unlocked by unauthorized persons. The essential object of the improvement is to provide a lock for freight-cars, by which to ascertain with unerring certainty on what section of a long line of road missing goods have been stolen, in order to render the particular section whereon the goods were lost accountable, instead of charging the loss *pro rata* upon all the sections, as is now the practice, owing to the want of any reliable means to fix with certainty upon the section encountering the loss.

Figure 1 is a side elevation of an ordinary padlock with one side of the case removed, to which I propose to apply my improvement. Fig. 2 is an elevation of the opposite side of the case. Fig. 3 is a horizontal section on the line *x x* of Fig. 1. Fig. 4 is a vertical section on the line *y y* of Fig. 1. Fig. 5 is a vertical section on the line *z z* of Fig. 4; and Fig. 6 is a side elevation of the key.

In this example I have represented an ordinary padlock, to which I have applied a secondary case, A, to contain the paper strip B and the working-rollers C C' for feeding said strip out through the case at D; and I have substituted for the ordinary key-post a tubular post, E, passing through the back side F of the lock-case, with a rose-clutch, G, on the end and a bit, H, on the side inside of the lock, to enter the notch I in the end of the key, for turning said post when the key turns to actuate the roller C, with which it clutches by a corresponding clutch, K, on it, with which it is held in contact by a spring, L. This roller C, together with the idle roller C' constitutes a pair of feed-rollers for forcing out the paper strip, which passes between them, and is firmly gripped between the rollers by the action of

the spring N, the said roller C' being mounted on a support, O, capable of moving toward or from roller C. M is a spring-pawl, to prevent backward rotation of the roller C. The rose-clutch is used to let the key-post turn back with the key when the latter is withdrawn from the lock, but would not be used if the key turned wholly around, as some do. A suitable guide, J, is employed to conduct the strip from the rollers to the orifice D; and a cutter, R, is fixed in the shell to facilitate the cutting or tearing of the strip.

This plan represents one arrangement by which the apparatus may be applied to locks already made; but other arrangements may be used; and, in applying it to new locks, such modifications in form and arrangement will be made as may be needful, according to the nature of the case; and I do not limit myself to any particular arrangement of the apparatus for actuating the paper strip; neither do I limit myself to actuating said apparatus through the medium of the key-post, for it may be done by the tumblers, or by the bolt, or any moving part, the same being provided with a pawl to actuate the rollers, or other equivalent means.

This numbered paper strip will not only indicate with unerring certainty between what stations—where the lock is opened and locked by duly authorized agents—it has been opened unauthorizedly, but it will be a check upon the station-agents, whose duty it is to open and relock them, by requiring each station-agent to forward the number torn off by him to the general agent for comparison; for if one agent neglects his duty the number torn off by the next one, which the first should have taken, being compared with the first number torn off at starting, will show the neglect of the delinquent agent.

Having thus described my invention, I claim as new and desire to secure by Letters Patent—

1. The combination, with a lock, of a numbered paper strip and apparatus for delivering a predetermined portion thereof through the lock-case each time the lock is unlocked, said apparatus being set in motion by the key, all substantially as specified.

2. A revolving key-post, E, of a lock, com-

bined with feed-rollers C C', and provided with a bit for turning it by the key, substantially as specified.

3. The combination of feed-rollers with a lock-case having a discharge-orifice for the delivery of a paper strip, substantially as specified.

4. The combination of the feed-rollers and

guide J with a lock-case having a discharge-orifice, substantially as specified.

The above specification of my invention signed by me this 13th day of December, 1871.

FRED. J. HOYT.
